FOREIGN PATENT DOCUMENTS

CN 308961217 * 11/2024

Primary Examiner — Paula Allen Greene

(74) Attorney, Agent, or Firm — Amin, Turocy & Watson,
LLP(57) **CLAIM**The ornamental design for an earphone, as shown and
described.

DESCRIPTION

FIG. 1 is a top, front and left side perspective view of an
earphone;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof; and,

FIG. 7 is a right side elevational view thereof.

The broken lines shown in the drawings illustrate portions of
the earphone that form no part of the claimed design.**1 Claim, 7 Drawing Sheets**(56)
